DESIGN FOR AN AUTOMOBILE HEATER SHELL OR SIMILAR ARTICLE

Fred M. Young, Racine, Wis.

Application November 4, 1935, Serial No. 59,364

Term of patent 3½ years

To all whom it may concern:

Be it known that I, Fred M. Young, a citizen of the United States, residing at Racine, in the county of Racine and State of Wisconsin, have invented a new, original, and ornamental Design for an Automobile Heater Shell or Similar Article, of which the following is a specification, reference being had to the accompanying drawing, which forms a part thereof.

Fig. 1 is a front elevational view of an automobile heater shell, showing my new design;
Fig. 2 is a side elevational view; and
Fig. 3 is a top plan view.

I claim:

The ornamental design for an automobile heater shell or similar article, as shown.

FRED M. YOUNG.
